UNITED STATES PATENT OFFICE

150,565

DESIGN FOR A COMBINED ASH TRAY AND
RECEPACLE OR SIMILAR ARTICLE

Nettie E. Graven, Wooster, Ohio

Application February 13, 1947, Serial No. 136,882

Term of patent 14 years

(Cl. D85—2)

To all whom it may concern:

Be it known that I, Nettie E. Graven, a citizen of the United States, residing at Wooster, in the county of Wayne and State of Ohio, have invented a new, original, and ornamental Design for a Combined Ash Tray and Receptacle or Similar Article, of which the following is a specification, reference being had to the accompanying drawing, forming part thereof.

Figure 1 is a top plan view of a combined ash tray and receptacle embodying my new design;

Fig. 2 is a front elevational view thereof; and

Fig. 3 is a side elevational view thereof.

I claim:

The ornamental design for a combined ash tray

and receptacle or similar article, substantially as shown.

NETTIE E. GRAVEN.
